Geo. W. Miller, Jr.

UNITED STATES PATENT OFFICE.

HARRY C. INNES, OF CINCINNATI, OHIO.

LATCHING DEVICE.

Application filed May 11, 1923. Serial No. 638,246.

My invention relates to latches and especially to latches for use on windows and similar structures. It is adapted particularly for use where it is desired to latch the structures in fixed relation to each other so as to prevent movement of same from the opposite side, as in the instance of windows, while at the same time preventing any one from disengaging the latch or tampering with it.

In the drawings Fig. 1 shows my latch applied to the lower sash and the casement of a window;

Fig. 2 is a cross section through the latch in Fig. 1;

Fig. 3 is a perspective view of one form of my latch;

Fig. 4 is a cross section of my latch applied to the upper and lower sash;

Fig. 5 is a front view of Fig. 4.

In the drawings in which like characters refer to like parts A is a window sash, B is the casement. In one form of my invention I fixedly attach to the sash A by screws D' 25 the latch plate D, and to the casement I fixedly attach the plate C by screws C'. The plates C and D are provided along their longitudinal edge with a plurality of separate integral portions, F on the plate 30 C, and E on plate D, turned or bent so as to form passages F' in the plate C and passages E' in the plate D. These portions E and F are preferably spaced and arranged so that when the passages E' F' are brought 35 into register the portions E and F alternate.

I provide a readily removable pin or locking member G which when the passages E', F' are in register is passed through the 40 passages thereby securely latching them in register and locking the adjacent members of a structure together against movement independently of each other.

In Figs. 4 and 5, I show one form of my 45 improved latch adapted to latch adjacent window sashes together in a number of different positions so that the window may be entirely closed or partially opened. In this form the plate C is attached to the top of 50 the sash A. In the sash I, I arrange slots or holes J. The plate D is provided with an extension or projections K arranged to be inserted in the slots or holes J. The extension or projections K are preferably arranged on the plate so as to extend from the

edge opposite the edge having the enlarged portion E so that when the extension or projections K are inserted into the slot or holes J the passage E' in the enlarged portion E may be brought into register with the passage F' in the enlarged portion F on the plate C so as to permit the pin or member G to be inserted in the passages to latch the plates together. In this way, dependent upon the position of the slot or holes J into which the extension or projections K are placed, the window may be securely latched either closed or partially opened, and the sashes so latched together to permit, if desired, movement of same as a single unit. 60 In Fig. 5, I show in the sash a series of openings or holes N into which the end of pin G may be inserted to latch the windows in any desired position. The number of different positions being dependent upon the 65 number of holes N.

Claims—

1. In combination with a plurality of separate structures comprising a plurality of window sashes and a frame therefor, said structures slidable relative to one another, a plate directly attached to one of said structures, a second plate attached to another of said structures, said plates being mounted in different planes and provided with passages 80 adapted to be brought into register, and loosely fitted in and means passing through said passages for connecting said plates together whereby the respective structures to which said plates are attached will be held 85 against substantial movement independently of each other.

2. In combination with separate structures one of which is movable independently of the other, a latch having a plurality of 90 separate members provided with passages adapted to be brought into register, one of said members being fixedly secured to one of said structures, the other member being detachably connected to the other structure at 95 any one of a plurality of positions, and means passing through said passages to hold the separate structures to which the members are operatively attached in fixed position in relation to each other.

3. In combination with a plurality of separately movable structures and a frame therefor, a latch having a plurality of separate members provided with passages adapted to be brought into register, one of 100 105 110

said members being fixedly secured to one of said structures, the other member being detachably connected to the other structure at any one of a plurality of positions, and 5 means passing through said passages to connect and hold the separate structures to which the members are operatively attached in fixed position in relation to each other, said means adapted to lock the connected 10 structures to said frame in any one of a plurality of positions.

4. In combination with a plurality of separately movable structures and a frame therefor, means, including a plurality of separate 15 plates having interfitting parts adapted to be detachably connected together, for latching said structures together so as to be mov-

able independently of said frame and means for latching said structures while latched together at one of a plurality of positions 20 with relation to the frame.

5. In combination with a plurality of separately movable structures and a frame therefor, a plurality of separate plates directly attached to said separate structures, and 25 means for detachably connecting said plates together and thereby connecting said structures, such connecting means adapted to latch such connected structures to said frame in any one of a plurality of positions. 30

In testimony whereof, I have signed my name to this specification.

HARRY C. INNES.
